UNITED STATES PATENT OFFICE.

EDWARD BOUMA, OF WATERLOO, IOWA.

COUNTING MACHINE FOR PRINTING PRESSES.

Application filed January 23, 1922. Serial No. 531,161.

To all whom it may concern:

Be it known that I, EDWARD BOUMA, a citizen of the United States of America, and a resident of Waterloo, Blackhawk County, 5 Iowa, have invented certain new and useful Improvements in Counting Machines for Printing Presses, of which the following is a specification.

My invention relates to improvements in 10 counting machines adapted to be attached to printing-presses or other oscillatory or reprocatory mechanism for counting and registering the sheets or other objects operated upon, and the object of my improvement is to construct the counting mechanism so that it may be initially set to show a desired aggregate of such objects to be operated upon, and to act subtractingly until all the objects are operated upon, means being 15 supplied whereby when said work has been accomplished the machine automatically functions to cause cessation of movement of the operating mechanism, and to energize a suitable signaling-device.

20 This object I have accomplished by the means which are hereinafter described and claimed, and which are illustrated in the accompanying drawings, in which Fig. 1 is a front elevation of said device with the swinging front closure removed. Fig. 2 is a horizontal section thereof taken on the line 2—2 of Fig. 4. Fig. 3 is a vertical section thereof taken on the line 3—3 of Fig. 4, and Fig. 4 is a longitudinal section thereof taken vertically adjacent one side wall. Fig. 5 is a front elevation of the device with the front closure in place. Fig. 6 is a detail side elevation of the ratchet mechanism, and Fig. 7 is a detail longitudinal section of one of the 25 terminals of the main circuit as mounted insulatedly in a side wall of the housing.

Similar numerals of reference denote corresponding parts throughout the several views.

30 The numeral 1 denotes an open front housing having at the top hinges 34 on which are suspended the swinging closure 31. Three spaced shafts 13—17 and 19 have their ends fixedly mounted in bearing orifices in the side walls of said housing and all lie in the same horizontal plane. A shaft 2 is also positioned across the interior of said housing below and a little to the rear of the shaft 13, is rotatably mounted in bearing openings in 35 the housing with its left hand end projecting

outwardly thereof and with a ratchet wheel 7 fixed thereon.

A handled rock-body 3 is medially pivoted on the outer end of the shaft 2 and is secured by means of a nut 9. The end of the rock-body opposite its handle part 3 is formed into a recess and widened engaging clamp 4 which may be fitted upon an oscillatory part of operating mechanism such as a reciprocatory printing press or any other mechanism adapted to handle or operate upon a succession of objects of a determined number. A pawl 6 is pivotally mounted at 5 on the handle end of said rock-body to engage teeth of the ratchet-wheel 7 to rotate the latter by successive steps as said rock-body is rocked upwardly. Upon that part of the rotatable shaft 2 which is most remote from said ratchet mechanism, the hub of a gear-wheel 8 is fixedly keyed at 10 to the shaft 60 to rotate positively therewith. To the left hand of said gear-wheel a number of like gear-wheels are rotatably mounted on the shaft 2 and each gear-wheel, including the one first mentioned, has a single detent 11 65 extending to the left from and terminally registering with one of the detents of the wheel, for a purpose to be described.

70 While any desired number of gear-wheels 8 may be employed, in the device shown, 75 four only are used.

75 A number of wide tooth gear-wheels 12 are rotatably mounted on the fixed shaft 13, in this case five gear-wheels 12 being employed, all but the extreme left-hand one of 80 of these being in mesh with the teeth of the gear-wheels 8, and the teeth of the gear-wheels 8 being narrower, mesh only with the left-hand parts of the wide teeth of the gear-wheels 12. As the gear-wheels 8 are spaced 85 apart by their leftward extending hubs, their single detents 11 may thus once during each rotation, mesh with right-hand parts of the teeth of the gear-wheels 12, whereby, in a well known way, as the gear-wheels are all 90 provided with ten teeth each, the denary wheels thus furnished, are advanced step-by-step thru the ratchet action through the space of one tooth each time. This arrangement of the respective gear-wheels with their 95 detents 11 causes the gear-wheels 8 beginning at the right in turn, to successively advance the next following gear-wheel 12 through the space of one tooth for each rotation of the antecedent gear-wheel 8. idler gear-wheels 18 are rotatably mounted upon the fixed shaft 17, are intermeshed with the gear-wheels 12, and are of the same size. The numeral 15 denotes a number of 5 gravity pawls mounted to rock on a fixed shaft 14 whose ends are fixed in orificed seats in said housing, said pawls having equi-angular detents 16 positioned above and adapted to be releasably meshed with teeth 10 of the gear-wheels 12.

The numeral 20 denotes five denary gear-wheels rotatably mounted upon said fixed shaft 19 being of the same width and adapted to mesh with the teeth of the idlers 18. The gear-wheels 20 are made of non-conducting material, and narrow cylindric rings 21 are fixedly mounted around the middle zones of said wheels, said rings bearing upon their outer faces like denary 20 numerals as shown at 33 from one to naught inclusive of the primary numerals. As shown in Fig. 2, the middle zones of the idlers 18 are annularly hollowed out to provide clearance for said rings 21. Each 25 wheel 20 has a longitudinal cylindric orifice 24 which, when all the wheels 20 are in certain relative positions, are in alinement, this position being the zero position of said denary wheels as indicated by the naught 30 numerals alined thereon as displayed through openings 32 in said front closure 31. The middle part of each orifice 24 is occupied by a short coiled compression-spring 23, and the end portions of each 35 orifice are occupied by anti-friction balls 22, and so that the action of the springs is to tend to push said balls outwardly to have rolling contact with the outer abutting end of the adjacent gear-wheel and also once 40 each rotation with the adjacent ball 22 in said adjacent gear-wheel. As said springs and balls are electrically insulated by the non-conducting material of said gear-wheel, they do not combine to provide a continuous 45 conducting assemblage through all the gear-wheels 20 until all these wheels have relatively assumed positions at zero. Bushings 26 of non-conducting material are inserted in openings in opposite side walls of 50 the housing 1 and are traversed by conducting pins 28 whose inner ends are widened at 25, the latter positioned for contact with the adjacent ball 22 once during each rotation. The balls 22 are prevented from 55 escaping from the orifices 24 from which they slightly project by slightly upsetting the angular edge of the orifice. The outer end of each pin 28 is threaded to receive a clamping nut 27, and these nuts secure 60 conductingly the terminals of conductors 29 and 30 which are in circuit with a source of electrical current 35. Any desired kind of electrically-actuated device, such as a signal-lamp 36, or a switch or mechanism 65 for throwing off the power of the printing

press or operating means, may be included in said circuit.

The denary numerals on each denary wheel 20 are arranged as shown in said Fig. 1, and with the object of indicating a process of subtraction during the successive step-by-step actuation of the wheels rather than by addition as in some other types of counting mechanism. The denary wheels 20 may be manually in turn rotated 75 appropriately in a certain direction to bring certain numerals 33 on the annular bodies 21 into an alinement horizontally to be seen through the openings 32 of the closure 31. For illustration, if a number of sheets are 80 to be printed, this total number is caused to be shown on the re-set denary wheels 20—21. When said ratchet mechanism has been set in operation by an oscillatory part of the printing press to which it is connected, the said gear-train is actuated step-by-step with each operation of the press in printing and delivering a sheet, the removal of each sheet being thus indicated by a subtraction of one from the total displayed on said denary wheels, and this goes on until all the sheets are printed and all the denary wheels arrive at their zero position as shown in Fig. 5. It is obvious that during all this time, the conducting springs 95 and balls 23 and 22 in the orifices in said wheels are never in continuous conducting contact, so that the circuit is not completed therethrough. At zero position, as these conductors are in contacting alinement with 100 each other and with the fixed terminals 25, the circuit is closed and the electrically actuated lamp or other device 36 is energized. In case an electro-magnetically actuated device of the proper kind is likewise included in said circuit, it may operate then to stop the action of the printing press instantly. It will be seen that this device automatically and accurately follows the action of the press and produces the 105 desired count of sheets without attendance. 110

It will be understood that various modifications in the elements of the device, their number, sizes and arrangements may be effected without thereby departing from the 115 principle of this invention or from the scope of its protection.

Having described my invention, what I claim as new and desire to secure by Letters Patent, is:

1. In a device of the character described, a shaft, denary wheels coaxially rotatably mounted thereon, and composed of non-conducting material, said denary wheels having longitudinal orifices adapted for alinement when all the wheels are in certain positions relative to a common denary numeral thereon, conductors mounted in said orifices to contact terminally only while said orifices are in alinement, conductors in cir- 125 130

- cuit with a source of electrical current and having terminals contacting with the outer ends of the conductors in the outermost denary wheels only while said orifices are in 5 said alinement, and mechanism for rotating said denary wheels to rotate each successive wheel beyond the preceding wheel one step for each rotation of such preceding wheel.
- 10 2. In a device of the character described, longitudinally alined non-conducting cylinders having numerals arranged circumferentially thereon, and having longitudinal orifices, conductors in said orifices for contact with each other when said orifices and numerals are alined, and an electrical circuit including terminals contacting with the conductors in the orifices of abutting cylinders.
- 15 3. In a device of the character described, longitudinally alined non-conducting cylinders having numerals arranged circumfer-
- entially thereon, and having longitudinal orifices, resilient conductors in said orifices for yielding contact with each other when said orifices and numerals are alined, and an electrical circuit including terminals contacting with the conductors in the orifices of abutting cylinders. 25
4. In a device of the character described, longitudinally alined non-conducting cylinders having numerals arranged circumferentially thereon, and having longitudinal orifices, resilient conductors and anti-friction conducting elements at each end thereof 30 in said orifices for contact with each other when said orifices and numerals are alined, and an electrical circuit including terminals contacting with the conductors in the orifices of abutting cylinders. 35
- 40

Signed at Waterloo, Iowa, this 4th day of January, 1922.

EDWARD BOUMA.
